BROOCH AND CLIPS COMBINATION

Gennaro Tavani, Brooklyn, N. Y.

Application October 17, 1936, Serial No. 106,072

8 Claims. (CL. 63—1)

This invention relates to jewelry and more particularly refers to improvements in pin and clips combinations of the type where a set of clips may be worn in the usual manner or may be combined to form a brooch with or without the addition of other ornamental elements.

A complete jewelry equipment for the well dressed woman generally calls for at least one set of clips and at least one brooch; on the other hand, a well dressed woman rarely wears too much jewelry at any one time so that generally the clips and the brooch are worn to the exclusion of each other.

It is therefore desirable to produce a set of clips adapted to be formed into a brooch to be worn at such times when the clips are not required, this making it possible to practically cut in half the expenditure which would otherwise be required by the necessity of procuring both a set of clips and a brooch.

The idea of combining a set of two clips as elements of a composite brooch is not in a broad sense new; but such arrangements as have come to my notice are generally open to objections on the ground of necessitating the use of specially constructed clips and also requiring complicated manipulations and resulting in the production of rather heavy and bulky brooch combinations.

The primary object of this invention is to provide a novel and improved type of brooch mounting adapted to be used and interlock with dress clips of ordinary construction in order to form a brooch assemblage requiring no change whatever in the construction of the clips themselves.

Another object is to provide a brooch mounting adapted to be used in combination with a set of dress clips in order to form a brooch, said brooch mounting being of a very simple and inexpensive construction and being easily connected or disconnected from the dress clips.

Other objects and advantages of the present invention will more fully appear as the description proceeds and will be set forth and claimed in the appended claims.

My invention is illustrated by way of example in the accompanying drawing, in which:

Fig. 1 is a rear view in elevation of a brooch embodying my invention;

Fig. 2 is a fragmentary longitudinal section thereof in an enlarged scale through line 2—2 of Fig. 1;

Fig. 3 is a front view in elevation of the brooch mounting shown in Fig. 1;

Fig. 4 is a vertical sectional view in an enlarged

scale illustrating the manner of connecting one of the clips to the brooch mounting; and

Fig. 5 is a similar view embodying my invention.

The brooch shown in Figs. 1 to 4, is composed of two dress clips 20, 21, each comprising a front ornamental member 22, 23 having a substantially straight inner end edge such as shown in dotted lines at 24, and being formed with a rearwardly projecting ridge such as shown at 25, 26 along 10 said inner edge.

On the ridge of each clip is permanently fixed a pivotal support 27, 28, for a spring clasp 29, 30 used for clamping the clip onto the coat lapel in the usual manner. Each pivotal support has a 15 base 31, 32 projecting beyond the inner edge of its corresponding ridge 25, 26, so as to form a clearance space 33, 34, with the rear surface 35, 36 of the corresponding front ornamental member.

So far as described the construction of the clips is one generally to be found in dress clips of standard construction purely intended for use as dress clips, as such. By virtue of my present invention two such dress clips may be joined to 25 form a brooch as shown in the drawing, without the necessity of making any change whatever in the construction of the clips themselves.

To this end, I provide a longitudinally extending body portion 37 from which depends a central tongue 38, the width of which corresponds to the distance between the inner edges of the pivotal supports 27, 28, when the two clips are arranged with their inner edges in abutting relation to each other as shown. Said mounting also 30 comprises two latch tongues 39, 40, one at each side of tongue 38, said latch tongues being laterally spaced from said tongue 38 as shown at 41, 42, a distance corresponding to that intervening between the outer edge of the base of the corresponding pivotal support and the inner edge of 35 the ridge carrying said support.

By virtue of this construction, the three tongues 38, 39, 40 can be inserted endwise along the pivotal supports of the two adjoining clips, the 45 tongue 38 resting against the exposed portion of the adjoining rear surface of the ridges, and tongues 39, 40 remaining within the clearance spaces 33, 34, under the bases of pivotal supports 31, 32 respectively, as clearly shown in Fig. 2.

The length of latch tongues 39, 40 is such that they extend for the full length of the pivotal supports and then snap into engagement with the outer end of said supports, the tip end of said latch tongues being to this end formed with 55

a tooth such as shown at 43, 44, engaging the outer end surface of said supports, as clearly shown in Fig. 4.

The two clips will thus remain securely joined to each other to form the brooch assemblage shown in Fig. 1. The tongues 38, 39, 40 are preferably frontwardly spaced from the body portion 37 in order to make it possible for said body portion to partly overlap the upper part of the 10 clasps 29, 30, as shown in Figs. 1 and 4. This makes it possible to locate the safety pin structure rearwardly extending from the rear surface of the body portion, at the proper height with respect to the longitudinal central line of the 15 clips, the preferred position for said safety pin structure being somewhat above said central line, as shown in the drawing. The safety pin structure comprises as usual a pivotal support 45, a longitudinally extending pin 46 having an end 20 pivotally connected to said support and a catch 47 at the other end for locking the free end of said pin in position.

In order to release a clip from the mounting it is sufficient to depress the tip end of the corresponding tongue 39 or 48 and slide the clip off in a downward direction with respect to Fig. 1. The fact that the clips are held in position by downwardly directed latch tongues makes it necessary to make absolutely sure that the 25 tongues are properly latched because otherwise a clip might slip down of its own accord.

In order to avoid this possibility the mounting can be made in the form shown in Fig. 5 where the latch tongues shown at 48 are bent upwardly 30 from the lower end 49 of the body portion 50, as shown at 51. With this type of mounting the 35 clips are not only locked by the latch tongues but are also supported thereby so that even if the tongues are not fully inserted to the latching 40 position the weight of the clips cannot cause them to slip off of their own accord.

In view of the fact that although the outer surface of the ridge in the clips shown is on the same plane with the inner edge of the clip, in 45 some cases the ridge may be inwardly spaced a short distance from said inner edge, so that the central tongue would then remain between the two ridges instead of overlapping them; the 50 claims are, therefore, to be read in the light of this possibility.

Other minor constructional details of my invention may vary from those shown without departing from the inventive idea. The drawing should, therefore, be understood as being intended for illustrative purposes only and not in 55 a limiting sense.

Accordingly, I reserve the right to carry my invention into practice in all those ways and manners which may enter, fairly, into the scope 60 of the appended claims.

I claim:

1. A mounting for dress clips of the type comprising a front ornamental member having a ridge rearwardly projecting from its rear surface 65 along its inner edge, a spring clasp, and a pivotal support for said clasp having its base made integral with said ridge and projecting beyond the inner side thereof so as to leave a clearance between said base and the rear surface of said front ornamental member, said mounting comprising two latch tongues spaced from each other a distance corresponding to the distance between the inner surfaces of their ridges when two clips are 70 arranged with their inner edges in abutting relation to each other, each tongue being insert-

able endwise under the projecting portion of the base of the pivotal support of the corresponding clip and having its outer end adapted to engage and interlock with the outer end of said support so as to form with said clip a composite brooch 5 assemblage.

2. A mounting for dress clips of the type comprising a front ornamental member having a ridge rearwardly projecting from its rear surface along its inner edge, a spring clasp, and a 10 pivotal support for said clasp having its base made integral with said ridge and projecting beyond the inner side thereof so as to leave a clearance between said base and the rear surface of said front ornamental member, said 15 mounting comprising two latch tongues spaced from each other a distance corresponding to the distance between the inner surfaces of their ridges when two clips are arranged with their inner edges in abutting relation to each other, 20 each tongue being insertable endwise under the projecting portion of the base of the pivotal support of the corresponding clip and having its outer end adapted to engage and interlock with the outer end of said support so as to form with 25 said clip a composite brooch assemblage, said mounting having a safety pin structure rearwardly extending from the rear surface thereof.

3. A mounting for dress clips of the type comprising a front ornamental member having a 30 ridge rearwardly projecting from its rear surface along the inner edge thereof, a spring clasp, and a pivotal support for said clasp having its base made integral with said ridge and projecting beyond one of the edges thereof so as to leave a 35 clearance between said base and the rear surface of said front ornamental member, said mounting comprising a central tongue and two side tongues each spaced from the axis of said central tongue a distance corresponding to the thickness of the 40 ridge at the corresponding side thereof, when two clips are arranged with their inner edges in abutting relation to each other, such of said tongues as will remain under the projecting portion of the base of each support when said tongues are 45 inserted endwise alongside said ridges, having their outer ends adapted to engage and interlock with the outer end of said support so as to form with said clips a composite brooch assemblage.

4. A mounting for dress clips of the type comprising a front ornamental member having a ridge rearwardly projecting from its rear surface along the inner edge thereof, a spring clasp, and a pivotal support for said clasp having its base made integral with said ridge and projecting beyond one of the edges thereof so as to leave a clearance between said base and the rear surface of said front ornamental member, said 55 mounting comprising a central tongue and two side tongues each spaced from the axis of said central tongue a distance corresponding to the thickness of the ridge at the corresponding side thereof when two clips are arranged with their inner edges in abutting relation to each other, such of said tongues as will remain under the 60 projecting portion of the base of each support when said tongues are inserted endwise alongside said ridges, having their outer ends adapted to engage and interlock with the outer end of said support so as to form with said clips a composite brooch assemblage, said mounting having a safety pin structure rearwardly extending from the rear surface thereof.

5. A mounting for dress clips of the type comprising a front ornamental member having a 70

ridge rearwardly projecting from its rear surface along its inner edge, a spring clasp, and a pivotal support for said clasp having its base made integral with said ridge and projecting beyond the inner side thereof so as to leave a clearance between said base and the rear surface of said front ornamental member, said mounting comprising a body portion and two latch tongues upturned from the lower edge and spaced from 10 said body portion, said tongues being spaced from each other a distance corresponding to the distance between the inner surfaces of their ridges when two clips are arranged with their inner edges in abutting relation to each other, each 15 tongue being insertable endwise under the projecting portion of the base of the pivotal support of the corresponding clip and having its outer end adapted to engage and interlock with the outer end of said support so as to form 20 with said clips a composite brooch assemblage.

6. A mounting for dress clips of the type comprising a front ornamental member having a ridge projecting from its rear surface along the inner edge thereof, a spring clasp, and a pivotal support for said clasp having its base made integral with said ridge and projecting beyond one of the edges thereof so as to leave a clearance between said base and the rear surface of said front ornamental member, said mounting comprising 25 a body portion, a central tongue upturned from the lower edge of and spaced from said body portion, and two side tongues also upturned from the lower edge of and spaced from said body portion, said side tongues being each spaced from 30 the axis of said central tongue a distance corresponding to the thickness of the ridge at the corresponding side thereof, when two clips are arranged with their inner edges in abutting relation to each other, such of said tongues as will 35 remain under the projecting portion of the base of each support when said tongues are inserted endwise alongside said ridges, having their outer ends adapted to engage and interlock with the outer end of said support so as to form with said 40 45 clips a composite brooch assemblage, said mounting having a safety pin structure rearwardly extending from the rear surface of said body portion.

7. A composite brooch consisting of a pair of dress clips each comprising a front ornamental

member having a ridge rearwardly projecting from its rear surface along its inner edge, a spring clasp, and a pivotal support for said clasp having its base made integral with said ridge and projecting beyond the inner side thereof so as to leave a clearance between said base and the rear surface of said front ornamental member, said clips being arranged end to end with their inner edges in abutting relation to each other, and a supporting mounting for said clips, said mounting comprising two latch tongues spaced from each other a distance corresponding to the distance between the inner surface of the ridges of said clips, each tongue being inserted endwise under the projecting portion of the base 15 of the pivotal support of the corresponding clip and having its outer end engaging and interlocking with the outer end of said support so as to form with said clips a composite brooch assemblage, and a safety pin structure rearwardly extending from the rear surface of said mounting. 20

8. A composite brooch consisting of a pair of dress clips each comprising a front ornamental member having a ridge rearwardly projecting from its rear surface along the inner edge thereof, a spring clasp, and a pivotal support for said clasp having its base made integral with said ridge and projecting beyond one of the edges thereof so as to leave a clearance between said base and the rear surface of said ornamental 25 member, said clips being arranged end to end with their inner edges in abutting relation to each other, and a supporting mounting for said clips, said mounting comprising a control tongue abutting against the two adjoining edge portions of 30 said clips, and two side tongues each spaced from the axis of said central tongue a distance corresponding to the thickness of the ridge at the corresponding side thereof, when two clips are arranged with their inner edges in abutting relation to each other, such of said tongues as will 35 remain under the projecting portion of the base of each support having their outer ends engaging and interlocking with the outer end of said support so as to form with said clips a composite 40 45 brooch assemblage, and a safety pin structure rearwardly extending from the rear surface of said mounting.

GENNARO TAVANI. 50
